UNITED STATES PATENT OFFICE.

DANIEL L. CHEEK, OF GAINESVILLE, GEORGIA.

VEHICLE-SHAFT.

SPECIFICATION forming part of Letters Patent No. 360,204, dated March 29, 1887.

Application filed August 23, 1886. Serial No. 211,681. (No model.)

To all whom it may concern:

Be it known that I, DANIEL L. CHEEK, a citizen of the United States, residing at Gainesville, in the county of Hall and State of Georgia, have invented a new and useful Improvement in Shafts, of which the following is a specification.

My invention relates to an improvement in poles and shafts for vehicles; and it consists 10 in the peculiar construction and combination of devices, that will be more fully set forth hereinafter, and particularly pointed out in the claims.

In the drawings, Figure 1 is a top plan view 15 of my invention, showing the shafts. Fig. 2 is a similar view of the same, showing the tongue or pole. Fig. 3 is a longitudinal section taken on the line $x-x$ of Fig. 2, and Fig. 4 is a detail rear elevation.

20 A B represent a pair of parallel cross-bars, which are connected together by means of blocks C on their under sides, near their ends, and by a block, D, on the under side of the transverse bars, at the center thereof. The said 25 blocks C D are provided with longitudinal openings, which are adapted to receive the rear ends of shafts E and of a pole or tongue, F. The said pole or tongue is inserted in the opening in the block D, and the said shafts 30 are adapted to be inserted in the openings in the blocks C.

G represents brace rods or straps which extend transversely across the under sides of the blocks C and D, and have their extremities 35 bolted to the under sides of the cross-bars A and B. Bolts H extend through the said brace-strap and through the blocks, and also through the cross-bars, so as to bolt the said brace-straps, blocks, and cross-bars firmly together. 40 On the undersides of the blocks, and arranged between the straps G, are bolted transverse straps I by means of bolts K, which also extend through the blocks and the cross-bars.

The blocks C and D form housings or boxes 45 to receive the rear end of the pole and the shafts, and the said pole and shafts are provided on their under sides with spring-detents L, having engaging-shoulders M on their undersides at their rear ends, to engage the straps 50 G at the rear ends of the blocks when the said pole or shafts are inserted therein.

The cross-bar A is provided with rearward-extending eyes N, adapted to be attached to the couplings on the front shaft-axle of the vehicle, and the cross-bar D is provided at its 55 extremities on its upper side with hooks N for the whiffletrees. The center of the said cross-bar D is provided with an opening or a hook for the attachment of a whiffletree.

When only one horse is to be attached to the 50 vehicle, the pole F is removed from the block D by first pressing upwardly on the rear end of its spring-detent, so as to cause the latter to disengage the strap G at the rear end of the block. This leaves the shafts E attached under the ends of the cross-bars, and adapted for 55 the attachment of a single horse to the vehicle, as shown in Fig. 1. When it is desired to attach two horses to the vehicle, the shafts are removed from the blocks C and the pole is 60 attached to the block D. The whiffletrees for 65 the double team are attached to the hooks N, and a double-tree is thus entirely dispensed with.

I do not desire to limit myself to the precise 70 construction hereinbefore described, as it is evident that modifications may be made therein without departing from the spirit of my invention.

Having thus described my invention, I 75 claim—

1. The combination of the cross-bars having the blocks or housings with the pole and shafts 80 adapted to be secured in the housings, and provided with spring automatic detents to lock 85 the same in the housings, substantially as described.

2. The cross-bars, one or more, in combination 90 with blocks or housings C D for the poles or shafts, located at the ends and the center of the cross-bars, and straps G, to attach the blocks or housings to the under side of the cross-bars, as set forth.

In testimony that I claim the foregoing as my 95 own I have hereto affixed my signature in presence of two witnesses.

DANIEL L. CHEEK.

Witnesses:
